(57) **CLAIM**

The ornamental design for a hinged electronic device, as shown and described.

DESCRIPTION

FIG. 1 is a front view of a hinged electronic device showing our new design, in an open configuration.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a top-front-right perspective view thereof.

FIG. 8 is a bottom-front-left perspective view thereof.

FIG. 9 is a bottom-rear-left perspective view thereof.

FIG. 10 is a top-rear-right perspective view thereof.

FIG. 11 is a front view of a hinged electronic device, showing our new design, in a closed configuration.

FIG. 12 is a rear view thereof.

FIG. 13 is a left side view thereof.

FIG. 14 is a right side view thereof.

FIG. 15 is a top view thereof.

FIG. 16 is a bottom view thereof.

FIG. 17 is a top-front-right perspective view thereof.

FIG. 18 is a bottom-front-left perspective view thereof.

FIG. 19 is a bottom-rear-left perspective view thereof; and, FIG. 20 is a top-rear-right perspective view thereof.

The broken line showings of on-screen graphics are for the purpose of illustrating environment that forms no part of the claimed design.

1 Claim, 11 Drawing Sheets
